CONTROL MECHANISM

George V. Fowler, Henderson, N. C.

Application November 17, 1944, Serial No. 563,961

2 Claims. (Cl. 200—52)

This invention relates to control mechanisms particularly designed for spinning frames of textile machinery.

In the operation of such machinery and in numerous other instances in the industry it is desirable to have an automatic stop mechanism whereby the operation of the machine may be terminated upon the completion of a particular operation as for instance when the bobbins of the spinning frame have received a predetermined amount of the material being wound thereon. Numerous means have been employed for automatically effecting this termination of the operating cycle of such machine.

Such previous means, however, are usually characterized by complicated mechanisms which are both delicate in their operation and require careful and frequent adjustments while at the same time usually acting with a time lag such that precise accuracy in the quantities of material wound on bobbins is not possible. Such devices for use in spinning frames are normally actuated by fluid pressure means which requires the presence of a source of fluid pressure to operate the devices and which frequently vary in their accuracy due to changes in pressure of the applied fluid as such may result from temperature differences.

Another problem which has presented itself in previous devices for effecting this control is the difficulty of providing simply a reset mechanism which may be easily actuated by an unskilled operator so as to institute a new cycle of operation after the automatic device has terminated the previous cycle and full bobbins have been replaced by empty ones and the device reset for a further loading.

It is an object of the present invention to overcome the above difficulties heretofore encountered and to provide a very simple, extremely accurate and easily reset control mechanism particularly designed for use in control of spinning mechanisms for textile plants.

A more specific object of the present invention is to provide an electrical control means which may be automatically operated by the material wound upon the bobbin so as to instantly terminate the spinning operation when a predetermined amount of material has been received by the bobbin.

A further object of the invention is to provide a device of the character set forth which may be reset to institute a new cycle of operation by a single manual movement in one direction of a reset plunger.

Another object of the invention is to provide a device of the character set forth in which the amount of the material to be wound upon the bobbin may be readily varied by the simple adjustment of a control screw without requiring either special tools or an experienced technician to accomplish the desired adjustment.

5 A further object of the invention is to provide a device of the character set forth which may be readily applied to existing types of spinning machines without modification of their present structural design.

10 A still further object of the invention is to provide a novel and efficient device of the character set forth which readily lends itself to economic manufacture so that a changeover of machinery from fluid pressure control devices to present simple electrical devices may be made without any substantial capital investment by the plant.

15 Further objects and advantages of my invention will be apparent from the following specification taken in conjunction with the accompanying drawing, wherein:

20 Figure 1 is a side elevation of the present invention as applied to the spinning frame of a textile machine;

25 Fig. 2, a horizontal sectional view taken through the device illustrated in Fig. 1;

Fig. 3, a vertical section taken along the lines 30 3—3 of Fig. 2; and

Fig. 4, a vertical section taken along the lines 35 4—4 of Fig. 2.

Referring more particularly to the drawing the spinning frame is illustrated as including a base 40 upon which is mounted the rotatable bobbin supports 11, the empty bobbin being illustrated by the numeral 12 to which thread 13 is supplied from the rotating guide 14 mounted on the base 11. The frame is illustrated as further including a vertical support 15 which is usually the end 45 member of the spinning frame. It will be understood that with each frame there are a plurality of the supports 11 and bobbins 12, the control mechanism being applied only to the end bobbin which thereby controls the operation of the entire series of bobbins.

The present invention comprises a cylindrical housing 16, the flanged end 17 of which is adapted to be secured to the support 15 as by screws 18. 50 The housing 16 is thus mounted horizontally adjacent to the end bobbin 12 and preferably in the rear thereof. The forward or flanged end of the housing 16 is closed by suitable closure block 19 which may be of wood or similar insulating

55 material and which is centrally apertured as at

20 to receive therethrough the operating shaft or rod 21 which extends through the member 15 terminating outwardly thereof in an operating knob 22.

The rod 21 is also preferably of insulating material such as wood and is provided with a transversely extending cotter pin 23 which projects from the sides thereof within the casing 16. The cotter pin 23 receives thereagainst a washer 24 which is urged towards the cotter pin by a coil spring 25, the rear opposite end of which abuts a central dividing and supporting block 26' which is also of insulating material and is centrally apertured to receive the inner end of the bar therethrough.

The inner extremity of the bar 21 is counterbored to provide a chamber 27 within which is mounted a spring 26 which normally urges outwardly a central metallic cap 28 which is made of conducting material such as copper. The side 20 of the cap is provided with an elongated aperture as at 29 to receive a retaining pin 30 carried by the terminal end of the rod 21 thus precluding movement of the cap from the end of the rod.

When the rod is moved to its full inward position, the metallic cap 28 is brought into engagement with a pair of spaced contactors 31 carried on the inner face of an end closure 32 for the casing 16, the closure 32 being otherwise formed of insulating material and the contactors 31 being individually connected with conductors 32', the arrangement being such that the contact of the head 28 will bridge the gap between the contacts 31 and establish electrical communication between the conductors 32' thus energizing the machine and initiating or maintaining the cycle of operation.

For retaining the rod in its inner position thus to establish electrical energy for the energization of the apparatus, the rod 21 is provided with a groove 33 adjacent which is fixedly mounted a bearing sleeve 34 preferably of metallic material. The face of the central block 26' has pivotally mounted thereon an operating controller 35 pivotally secured as by the screw 36. The controller 35 is pivotally mounted above the rod 21 so that the external projecting portion which extends through an arcuate slot 38 of the housing 16 normally urges by gravity the arm 35 in counter clockwise direction as shown in Fig. 4 so as to engage the slot 33 and retain the rod in its inner position against the tension of the spring 25. The forward externally extending terminal end of the controller 35 is provided with a feeler head 39 mounted upon a threaded member 40 which extends through the terminal end of the arm controller 35 and is adjustably secured in position by a locknut 41.

In the operation of the device when the material wound upon the bobbin has reached a predetermined height which is adjustably determined by the position of the feeler head 39 a vertically movable portion of the mechanism will engage the head 39 and thus lift the controller 35 thus removing it from the groove 33 and permitting the rod 21 to spring outwardly under the influence of the spring 25 whereby the head 28 will be disengaged from the contacts 31 and the passage of current between the conductors 32' will be stopped thus terminating the cycle of op-

eration of the machine. When the bobbin is removed the arm 35 will again drop by gravity but the groove 33 in the rod 21 will be positioned on the other side of the member 26' in which the rod is journaled so that the arm will rest upon the metallic sleeve 34 until such time as the operator manually moves the rod 21 inwardly against the tension of the spring 25 thus establishing contact between the members 31 at which time the arm will again drop into the groove 33 and will thus retain the rod in the operative position till such time as the vertically movable portion of the mechanism again actuates the arm 35 to terminate the flow of power to the machine.

It will be obvious to those skilled in the art that various changes may be made in the invention without departing from the spirit and scope thereof and therefore the invention is not limited by that which is shown in the drawing and described in the specification but only as indicated in the appended claims.

What is claimed is:

1. Control mechanism for spinning frames of textile machinery each of which spinning frames has a movable part, said control and mechanism comprising a cylindrical housing, means for securing said housing to a support adjacent a spinning frame, a closure member in one end of said housing, spaced electrical contacts mounted on said closure member, spaced supporting members in said housing having apertures in alignment with the space between said contacts, a switch element reciprocable in said aligned apertures and in one extreme position being adapted to complete the circuit between said spaced contacts, cushioning means on one end of said switch element for cushioning the engagement between the switch element and said contacts, resilient means for urging said switch element toward open switch position, means whereby said switch element may be manually moved toward closed position, and a gravity operated latch for maintaining said switch element in closed position whereby when said movable part engages and elevates said latch the switch element will be automatically moved to break the circuit.

2. Control mechanism for spinning frames of textile machinery each of which spinning frames has a movable part, said control and mechanism comprising a cylindrical housing, means for securing said housing to a support adjacent a spinning frame, a closure member in one end of said housing, electrical contacts mounted on said closure member, a switch element reciprocably mounted in said housing and in one position being arranged to complete the circuit between said contacts, means on one end of said switch element for cushioning the engagement between the switch element and said contacts, resilient means for urging said switch element toward open switch position, means whereby said switch element may be manually moved toward closed position, and a latch for maintaining said switch element in closed position whereby when said movable part engages and elevates said latch the switch element will be automatically moved to break the circuit.
